DESIGN FOR A MATCH COVER

Robert Goodman and Charles Nabelle,
New York, N. Y.

Application February 26, 1936, Serial No. 61,363

Term of patent 3½ years

To all whom it may concern:

Be it known that we, Robert Goodman, and Charles Nabelle, citizens of the United States of America, residing in Manhattan, county of New York, and State of New York, have invented a new, original, and ornamental Design for a Match Cover, of which the following is a specification, reference being had to the accompanying drawing, forming part thereof, wherein,

We claim:

The ornamental design for a match cover, substantially as shown, and described.

ROBERT GOODMAN.
CHARLES NABELLE.
